UNITED STATES PATENT OFFICE.

EDSON J. SMITH, OF BOSTON, MASSACHUSETTS, ASSIGNOR TO JOHN CARTER & CO., OF SAME PLACE.

APPARATUS FOR FINISHING THE EDGES OF CARDS AND PAPER.

SPECIFICATION forming part of Letters Patent No. 416,869, dated December 10, 1889.
Application filed May 21, 1888. Serial No. 274,488. (No model.)

To all whom it may concern:

Be it known that I, EDSON J. SMITH, of Boston, in the county of Suffolk and State of Massachusetts, a citizen of the United States, have 5 invented a new and useful Apparatus for Finishing the Edges of Cards, Paper, &c., of which the following is a full, clear, and exact description, reference being had to the accompanying drawings, forming a part of this 10 specification, in explaining its nature.

The invention relates to an apparatus for finishing or beveling the edges of cards, paper, &c., and which comprises, essentially, a clamp 15 for presenting the edges of the cards or paper to a cutting disk or cylinder having cross clearing-recesses formed therein and separate or independent cutting implements extended therefrom into said clearing-recesses and beyond the surface of the disk or cylinder. This 20 disk or cylinder is mounted upon a shaft, is adapted to be rapidly rotated, and for certain kinds of work is used in connection with a gage.

In the drawings, Figure 1 is a view in plan 25 illustrating the invention and showing especially the manner of presenting a stack of clamped cards to the cutting-cylinder. Fig. 2 is a view in end elevation thereof. Fig. 3 is a view in front elevation of the cutting-cylinder, its gage, shaft, and support for the same. Fig. 4 is a view in end elevation thereof. Fig. 5 is a view in enlarged cross-section of the cutting-cylinder. Fig. 6 is a view, enlarged, 30 in plan of the cutting-cylinder. Figs. 7 and 8 illustrate a smaller cutting-cylinder than is shown in the other figures. Figs. 9 and 10 show cards the edges of which have been finished. Figs. 11, 12, 13, and 14 show different forms of cutting or gouging tools or implements.

A represents the cutting disk or cylinder. It is mounted upon a shaft a, supported by the bearings a', and having a fast pulley a² and a loose pulley a³. The cylinder, preferably, is made of metal, and has extending 45 across it from end to end the clearing-recesses a⁴, which are preferably enlarged gradually from one end of the cylinder to the other. The cylinder also has the holes a⁵ extending 50 across the same tangentially and having one opening at the edge of a clearing-recess a⁴.

These holes receive the cutting implements or tools a⁶, and each cutting implement is secured in its hole by means of a screw a⁷, which screws into a radial hole a⁸, the radial hole 55 extending to meet the cross-hole a⁵. This construction not only serves to secure the tool to the cylinder, but also to permit it to be adjusted or moved to vary the position of its cutting-edge a⁹ in relation to the surface a¹⁰ 60 of the cylinder, and also to permit the tool or cutter to be properly set after it has been ground.

The cylinder or disk may have one cutting-tool and clearing-recess or two cutting-tools 65 and one clearing-recess, as represented in Fig. 8, or it may have a larger number of cutting-tools and clearing-recesses, as represented in Figs. 5 and 6, where there are shown three clearing-recesses and three lines of cutting 70 tools or implements, one for each clearing-recess, and in this invent I prefer to arrange the cutting-tools so that no one of them shall come in line circumferentially with others back of it.

For certain work a gage is desirable, and I have represented it in Figs. 1, 3, and 4 at B, and as provided with a disk b, having a hub b', secured to the shaft a by a set-screw b², and as also having a recess b³ in its face slightly 80 larger than the cylinder A. This construction—viz., the recess and the set-screw—enables the gage to be adjusted laterally in relation to the cylinder. The cards or paper are arranged in a stack and are held between 85 the two blocks c c' of a clamp C, the clamp having a screw c², whereby one block is made movable and held in relation to the other block, and the cards are tightly confined in the clamp between these two blocks in a manner to expose the edge which is to be finished, and they preferably are arranged somewhat out of line, so that the edge of one card or sheet of paper extends slightly beyond the edge of the one immediately over it. (See 90 Fig. 2.)

In operation the operator takes the stacked cards, sheets of paper, or other material to be finished in this manner and secures the same in the clamp, and then presents the edge or 100 edges to be finished to the cutting-cylinder. If what is termed a "ragged edge" is required,

then the form of cylinder represented in Figs. 7 and 8 is preferable and the use of the gage is dispensed with, and the clamp is moved horizontally back and forth in relation to the disk or cylinder as it is rotated. This produces a very ragged and irregular finish capable of infinite variation. (See Fig. 10.) When it is desired that only a portion of the edges of the cards or paper shall be finished by the cutter, then the gage B is employed, and preferably a wider cylinder, and the clamp, instead of being moved horizontally, is moved vertically in relation to the cylinder, one edge of the stack of cards or paper being held against the face of the gage. (See Fig. 1.) This also provides the edge with a more regular finish—that is, each knife or cutting-tool of the cylinder removing only the paper upon a given line. (See Fig. 1.) The form of the finish, especially where it is a regular finish, depends upon the form of the cutting-edge of the cutting-tool. It may be rounded, as represented in Fig. 11, or it may be V-shaped, as represented in Fig. 12, or its edge may have any other desired configuration. The cutting-tool is preferably formed of steel, and has its cutting-edge a^1 formed by the bevel a^{11} , and the surface a^{12} preferably being flat. It will be observed that the surface a^{10} of the cylinder or disk acts as a rest, against which the edge of the assembled cards bears during the operation of the cutters, so that the cutters can make a cut no deeper than the cutting-points extend from said surface.

Having thus fully described my invention, I

claim and desire to secure by Letters Patent of the United States—

1. The combination, with a rotary shaft, of a cylinder A, secured thereto and consisting of a single solid body having one or more longitudinal clearing-recesses extending entirely across its face, a smooth bearing-surface a^{10} between said recesses, tangential holes opening into said recesses, and radial holes opening into said tangential holes, the cutting-tools a^6 in said tangential holes, with their cutting ends projecting beyond the surface of the cylinder at said clearing recess or recesses, and the set-screws a^7 , for securing said tools in place. 40

2. The combination, with a rotary shaft, of a cylinder A, secured thereto and consisting of a single solid body having longitudinal clearing-recesses extending entirely across its face, tangential holes opening into said recesses, and a smooth bearing-surface a^{10} between said recesses, and cutting-tools secured in said tangential holes and arranged out of line circumferentially around said cylinder. 55

3. The combination, with a rotary shaft, of a cylinder A, secured thereto and having longitudinal clearing-recesses, a smooth outer bearing between the same, cutting-tools carried by said cylinder, and the rotary gage B, secured to said shaft adjacent to said cylinder. 60

EDSON J. SMITH.
